ABSTRACT OF THE DISCLOSURE

Disclose a method and apparatus for drying hair whereby a vacuum pump is used to draw ambient air through segments of wet hair in the form of rolls or pin curls. Discloses additionally, a specially designed roller, cover and a clip as well as a connecting mechanism for connection to low pressure tubular members and a housing whereby the tubular members are slidably adjustable.

Field of the invention

This invention relates to a process and apparatus for drying hair and more particularly to hair dryers utilizing streams of low pressure to draw ambient air through a mass of wet hair to dry same.

Description of the prior art

In the process of setting hair, it has been the practice to first shampoo the hair and rinse same. Thereafter, the hair is combed smooth and styled by the placement of various rollers and by the sculpturing of certain of the curls. In order to style the hair, the hair is sectioned on the scalp according to the diameter of the roller. The hair is lifted vertically and then rolled down on its own base adjacent the scalp and secured thereto by means of a clip. Thereafter, the hair is dried by placement of the head beneath a dryer designed to dry by convection at a temperature of about 100° F. for about 30 to 45 minutes. In certain instances, especially with bleached hair or with hair which is brittle or has broken ends, subjecting the hair to this temperature for this length of time is undesirable. Nevertheless, due to the fact that bleached hair has had color granules and its protective coating removed, such hair tends to absorb more water and thus requires a drying treatment for this length of time or, in some instances, even longer.

It is desirable, therefore, to provide a method and apparatus for drying the hair more quickly and at a lower temperature. The broad concept of applying tubular members to hair forming devices, such as rollers and clips, to force air through the wet hair on said devices, to dry the hair or cool the scalp is broadly old. See, for example, U.S. Patent 2,110,463 Ferguson; 2,188,924 Rockwood; 2,097,808 Zoberg; 3,199,218 Bean; 3,241,560 Willat; and 3,265,075 Edam et al. However, these proposals, insofar as relevant to hair drying, have utilized a forced air supply, preferably heated.

Since it is necessary to force the air through the hair, it is also necessary to utilize specially designed rollers and clamps whereby the air is injected at one end of the roller and is then forced through the hair wound around the roller. The bulky attachment of the tubular member to one end of the roller places a limitation on the hairdresser in his placement of rollers in blocking and spacing. Further, the attachment of the roller to the tube is either

2

time consuming or requires complicated and expensive apparatus.

Summary of the invention

Basically, my invention involves a method and an apparatus for achieving the method of drawing ambient air through a shaped segment of wet hair to dry the hair and simultaneously cool the scalp, through the use of a tubular member held in close proximity to the segment of hair and in communication with a source of low pressure. Apparatus for achieving the method involves specially designed rollers and covers for said rollers and simple and quick methods of connecting said covers to the rollers and to the low pressure tubular members.

Still another object of the invention is a specially designed self-aligning connecting mechanism for the hair holding devices and the tubular members which are centrally located so as not to place a limitation on the hairdresser in blocking and sectioning the scalp.

Still another object of this invention is the provision of individually adjustable tubular members to allow maximum freedom for the hairdresser.

Still another object of this invention is a specially designed clamp and connecting means for drying pin curls.

Still another object of this invention is the provision of connecting means between the hair holding device and the tubular members which are simply and quickly connected and disconnected and which are simply and inexpensively manufactured.

Brief description of the drawings

FIG. 1 is a side elevation partially diagrammatic, of the apparatus of my invention in use.

FIG. 2 is a side elevational view, partially in section, of the housing illustrating the low-pressure chamber, the distribution plate, and the relation of the tubular members to each other in said housing.

FIG. 3 is an enlarged sectional view taken on lines 3—3 of FIG. 2, illustrating the structure and relation of one of the hollow cylindrical members to the distribution plate and to a tubular member slidably positioned therein.

FIG. 4 is a plan view of the distribution plate taken along lines 4—4 of FIG. 2.

FIG. 5 is a front elevation of the roller and cover of this invention.

FIG. 6 is a sectional view of the cover taken along lines 6—6 of FIG. 5.

FIG. 7 is an end elevation of the roller taken along lines 7—7 of FIG. 5.

FIG. 8 is a front elevation of a modified cover.

FIG. 9 is a sectional view of a clamp and a connecting piece specifically designed for pin curls.

FIG. 10 is a bottom plan view of the clamp and connecting piece taken along lines 10—10 of FIG. 9.

FIG. 11 is a view in perspective, illustrating the process of rolling the hair onto a roller.

FIG. 12 is a view illustrating the special clamp of this invention being fitted onto a pin curl.

FIG. 13 is a plan view of the top plate of the housing in a modified form wherein the cylindrical members are recessed in counterbores in the bottom of the plate and the plate contains arcuate openings around its periphery to allow the low pressure to enter the lower chamber of the housing.

FIG. 14 is a longitudinal sectional view of a modification of the apparatus illustrating a cylindrical member

mounted in the counterbore of the plate shown in FIG. 13 and with the tubular member in extended position.

FIG. 15 is a fragmentary longitudinal sectional view, illustrating the gasket of the tubular member in sealing relation with the ports of the cylindrical member and the tubular member in fully retracted position.

Description of the preferred embodiments

Referring now to the drawings, and specifically to FIG. 1, the vacuum pump is connected to vacuum or low pressure line 2 which runs to housing 3. The tubular members 4 are connected to the roller assemblies 5 containing the segments of wet hair wound thereon. The housing 3 per se has a vacuum or low pressure inlet 6 which enters into the low pressure chamber 7. The low pressure chamber is separated from lower chamber 16 of the housing by the distribution and guide plate 8 containing a series of circular openings 10. Connected to each of the circular openings 10 is a hollow cylindrical member 11 which depends therefrom and passes through guide plate 9 and is secured to base plate 12. Each of the plates 8, 9 and 12 are held in position by tie rod 13 which is secured by nut 14. The outer casing wall 15 of housing 3 encloses the entire assembly and is sealed by O rings (not shown) around plates 8, 9 and 12. As is best shown in FIG. 3, each of the hollow cylindrical members 11 contains a tubular member 4 slidably mounted therein. The tubular member 4 for purposes of description, contains an inner end portion 20 which normally is always inside the hollow cylindrical member 11 and is mounted in lubricated gasket 25. The outer end portion 21 of tubular member 4 is normally outside of the hollow cylindrical member 11 when in use but is some times slidably pushed up into the cylindrical member 11 when the apparatus is out of use. The end of the tubular member 4 contains a hollow spherical member 24 which fits into a socket 40 of cover 34. Loosely positioned above the spherical member 24 is an O ring 23 which tends to seal any space between the walls of socket 40 and the spherical member 24 when the apparatus is in use.

Referring now to FIG. 5, the roller assembly 5 consists of roller 30 which has a foraminous body 31 made of mesh wire or other suitable material formed into a roll. The foraminous body 31 is closed at either end by an imperforate end member 32 secured into position by a metal cap which forms a slight ridge at the point 33 at either end of the roller.

The cover 34, which in cross section is semicircular, contains lateral gripping edges 36 along its axial length. Located close to the ends of the roller on the inside are stops 37 which are adapted to register with ridge 33 formed by the metal caps holding the imperforate end pieces in position. Thus, as is shown in FIG. 7 in broken lines, there is formed a space 38 between the radius of the cover 34 and the roller 30.

Located preferably centrally, relative to the ends of the roller and cover, is a socket 40 containing perforate bottom 41. Ports 42 extending through the perforate bottom and the body of the cover 34 communicate between the socket 40 and the space 38 surrounding the roller 30. Thus, there is communication between the tubular member 4 and the ports 42 to the foraminous roller body 31.

Referring now to FIGS. 9 and 10, there is illustrated a special clamp containing a socket member 40 for drying pin curls. In this instance, the clamp 50, which is described in detail in U.S. Patent 2,467,487 contains an upper leg 51 and a lower leg 52. Surrounding the two legs is an elastic member 53 which tends to draw the two legs toward each other. As will be seen, the upper leg 51 is mounted above the perforate bottom 41 of the socket member while the bifurcated lower leg 52 is mounted below the perforate bottom 41. The ports 42 extending through the perforate bottom 41 thus draw air from the area in the center of the curl into the low pressure tubular

member 4 through cylindrical member 11 to low pressure chamber 7 onto the vacuum pump. By this means ambient air outside of the pin curl is pulled through the hair and thus dries the curl and simultaneously cools the scalp.

In the modification of the top plate 70, illustrated in FIG. 13, instead of holes 10, as shown in FIG. 4, there are provided a series of counterbores 72, into which the hollow cylindrical members 11 are mounted. Around the periphery of the plate are a series of arcuate openings 71, so that both upper chamber 7 and lower chamber 16 become low pressure vacuum chambers. At the top of the wall of each cylindrical member 11 are a series of ports 73.

Thus, when the tubular member 4 is extended as shown in FIG. 14, the ports are open. However, when the tubular member is fully retracted, as shown in FIG. 15, gasket 25 comes into sealing engagement with ports 73 thus closing the tubular member from communication with the low pressure zone in chamber 16 of the housing.

This allows an operator to utilize only a portion of the total number of tubular members without excessive loss of suction since the retracted members are effectively sealed off from the vacuum chambers by means of gasket 25 in sealing engagement with ports 73. The gasket 60 in base plate 12, surrounding the cylindrical member 11, eliminates any loss of the vacuum at this point.

FIG. 11 illustrates the normal process of rolling the hair onto the roller 30. After the hair is rolled, the cover 34 is fitted over the rolled hair so that the stops 37 engage with the hair surrounding ridge 33. Thus the hair strands themselves are located in the free space 38 between the roller 30 and the cover 34. The tubular member 4 is connected to the cover 40 merely by inserting the spherical member 24 into socket 40 which by means of the low pressure is pulled immediately into position and also pulls O ring 23 into sealing engagement between the spherical member 24 and socket 40. Ambient air is thus drawn through the strands of hair around the roller 40 through the foraminous body 30 into the free space 38 and through the strands of hair wound thereon through ports 42 into socket member 40 and thus to low pressure conduit 4 and hollow cylindrical member 11 to low pressure chamber 7 through low pressure inlet 6 through low pressure line 2 to the vacuum pump 1. The hair wound on the roller thus is dried quickly at low temperature to offer comfort and convenience to the customer as well as eliminating any possibility of danger to the hair or the scalp through the use of high temperatures for prolonged periods.

As is illustrated in FIG. 12, a pin curl is formed conventionally by wrapping a few strands of hair around the finger or other circular object and is then held in place by means of the specially designed clamps illustrated in FIGS. 9 and 10. As shown in FIG. 12, the curl is anchored into position by engagement of lower leg 52 of the clamp 50 against the perforate bottom 41 of the socket member 40. Air is thus drawn through the circlet of hair forming the curl to the center and thence through ports 42 and into low pressure line 4 back to the vacuum pump as previously described.

In practicing my invention, I have found that the vacuum pump can be powered by a one and one-half horsepower motor and I have designed the housing so that the low pressure formed in chamber 7 is such that about 13 cubic feet of air per minute is drawn through each of the hollow cylindrical members 11 and thus through each of the slidably positioned tubular members 4. Further, this housing 3 is divided between low pressure chamber 7 and a series of low pressure streams 11 and 4 by means of distribution plate 8. The tubular members 4 are preferably made of material known in the trade as Tygon and it has been found that this material easily slides on a lubricated gasket such as Teflon 25 into sealing engagement so that there is very little leakage

between the cylindrical member 11 and the tubular member 4. The use of the spherical member 24 to seat in the socket 40 provides a quick connect and disconnect since the spherical member 24 is actually drawn or pushed into place by the outside air and the slidible O ring 23 automatically snaps into sealing engagement to prevent leakage at this point. Further, the spherical member 24 is self-aligning in that if a tube is twisted, there is essentially no strain on the roller 30 or cover 34 or on the scalp.

By use of this invention, I have been able to provide comfortable hair drying with little or no danger to the hair or scalp and have reduced the drying time from 30 to 45 minutes down to 10 or 15 minutes.

I claim:

1. A method of drying hair comprising the steps of:
  - (A) forming wet hair into a plurality of individual configurations by wrapping said hair on individual, hollow, foraminous members having closed ends,
  - (B) placing a cover element having at least one aperture therein over a portion of each hair configuration and attaching each cover to each member,
  - (C) connecting a source of vacuum to the aperture in each cover element for creating a pressure zone lower than the ambient pressure in each member and
  - (D) drawing ambient air through each foraminous member into the thus created low pressure zones and through each cover element to said vacuum source so that the wet hair is dried by ambient air.
2. The method according to claim 1 wherein the rate of ambient air flow through each cover member is approximately 13 cubic feet per minute.
3. A hair drying apparatus comprising:
  - (A) a vacuum pump,
  - (B) a chamber in communication with said vacuum pump,
  - (C) a plurality of tubular members leading from said chamber and in communication therewith,
  - (D) means for holding a mass of hair to be dried by passage of ambient air therethrough, including:
    - (1) an elongated radially foraminous hollow cylindrical member having an imperforate closure at both ends for rolling a segment of wet hair, and
    - (E) connecting means for connecting said means for holding a mass of hair and said tubular members together comprising:
      - (1) a cover including:
        - (a) an axially elongated member, generally semicircular in cross section, and having lateral gripping edges for frictional engagement over said cylindrical member,
        - (b) a stop for holding said cover in spaced relation from said cylindrical member except at the point of contact of the lateral gripping edges of said cover,
        - (c) a second connecting and communicating means located along the axial length of said cover for connection of said tubular member thereto, and communication of said tubular member therewith, and
        - (d) an aperture in said cover in communication with said connecting and communicating means.
  4. A hair drying apparatus, as defined in claim 3, in which the second connecting and communicating means is in the form of a socket.
  5. A hair drying apparatus, as defined in claim 4, the further combination therewith of a spherical member connected to the free end of said tubular member for seating in said socket.
  6. A hair drying apparatus, as defined in claim 5, the further combination therewith of a sealing member slidably located above said spherical member, on said tubular

member for sealing the area surrounding the point of contact of said spherical member with said socket.

7. Apparatus for drying hair comprising:
  - (A) a vacuum pump,
  - (B) a housing in communication with said vacuum pump comprising:
    - (1) an outer casing,
    - (2) a distribution plate including a plurality of circular openings,
    - (3) a plurality of cylindrical members, said cylindrical members being mounted in airtight connection to said circular openings,
  - (C) a plurality of flexible tubular members, equal in number to said number of cylindrical members, each of said tubular members having inner end portions slidably mounted in a separate cylindrical member and each of said tubular members having outer end portions mounted for independent movement between a retracted position, partially within said cylindrical member, and an extended position, outside said cylindrical member,
  - (D) hair shaping means, detachably connected to said outer end portions of said tubular members when in extended position, and which are adapted to be disposed in intimate relation with the hair of a person using the apparatus.
8. Apparatus for drying hair, as defined in claim 7, in which:
  - (A) each of said cylindrical members are closed at one end, and
  - (B) each of said cylindrical members have an open port in the wall near its closed end,
  - (C) the further improvement therewith of a gasket mounted on the upper end of each tubular member, so as to be in sealing position with said port, when the tubular member is in retracted position, and out of engagement with said port, when the tubular member is in extended position.
9. A hair roller for drying hair which comprises:
  - (A) an elongated radially foraminous hollow cylindrical member having an imperforate closure at both ends, for rolling a segment of wet hair,
  - (B) a cover including:
    - (1) an axially elongated member, generally semicircular in cross section and having lateral gripping edges for frictional engagement over said cylindrical member,
    - (2) a stop for holding said cover in spaced relation from said cylindrical member except at the point of contact of the lateral gripping edges of said cover,
    - (3) connecting and communicating means, located along the axial length of said cover for connection of a low pressure conduit thereto, and communication of said conduit therewith,
    - (4) an aperture in said cover in communication with said connecting and communicating means.
10. A hair roller, as defined in claim 9, in which:
  - (A) the cross sectional periphery of said cover extends more than 180° and the lateral gripping edges are in frictional engagement with said cylindrical member so as to be in close proximity to the scalp.
11. A hair roller, as defined in claim 9, in which the connecting means is centrally located relative to the ends of said cover.
12. A hair roller, as defined in claim 9, in which:
  - (A) the connecting and communicating means is in the form of a socket.
13. A hair roller, as defined in claim 9, in which:
  - (A) the imperforate closure extends over the end of said radially foraminous hollow cylindrical member to form a slight ridge around the peripheral edge of

the end of said cylindrical member for engagement with the lateral gripping edges of said cover.
